UNITED STATES PATENT OFFICE.

ADOLPH A. HUNZIKER, OF ST. LOUIS, MISSOURI.

FILE AND BINDER.

SPECIFICATION forming part of Letters Patent No. 605,717, dated June 14, 1898.

Application filed November 29, 1897. Serial No. 660,112. (No model.)

To all whom it may concern:

Be it known that I, ADOLPH A. HUNZIKER, of St. Louis, in the State of Missouri, have invented certain new and useful Improvements in Files and Binders, of which the following is a full, clear, and exact description.

The invention relates more particularly to files and binders for a series of separate leaves forming a ledger or other account-book; and the object of the invention is to improve the construction of the fasteners or retainers for the leaves, whereby the leaves may be removed and replaced with convenience and despatch.

15 The invention consists in the novel features hereinafter described, and defined in the claims.

Reference is to be had to the accompanying drawings, forming a part of this specification, 20 in which similar characters of reference indicate corresponding parts in all the figures.

Figure 1 is a perspective view of a file or binder embodying my invention, showing a cover open or thrown back to expose the leaf fastening or retaining devices, the latter being shown closed or in normal position. Fig. 2 is a similar view showing the leaves thrown to the right and left and the leaf-retainers open for the removal or insertion of the leaves.

30 Fig. 3 is a detail perspective view showing one of the leaf-fasteners and the securing-plate therefor. Fig. 4 is a transverse vertical section of the file and binder closed and on an enlarged scale. Fig. 5 is a longitudinal elevation showing the fasteners and the plate or strip that carries the same, parts being sectioned on the line 5 5 of Fig. 6; and Fig. 6 is a plan view of the said plate and fasteners, parts being sectioned on the line 6 6 of Fig. 5.

35 In constructing a file and binder in accordance with my invention a suitable cover or case A is provided to open substantially flat, and to one of the covers, adjacent to the back A, a plate or strip B is secured, on which 40 there are held in a novel manner the retainers or fasteners C for the ledger or other account leaves D.

The fasteners C are composed of two members c c', Fig. 3, mounted for pivotal move-

ment, the members being each of semicircular 50 or U shape or equivalent form, and they extend through recesses b in the sides of the plate B and meet at the under side of said plate, where they are pivotally united by a wire c² or its equivalent, the wire in the instance 55 shown having its ends passed upward through the plate B and riveted. The plate B between the recesses b is bent upward, as at b', to better accommodate the fasteners. There is sufficient space provided in practice at the 60 back of the plate B to permit a pivotal movement of the fastener members in opening and closing. At the free ends the members c c' are given such mating conformation as to cause them to engage with each other, where- 65 by they will be held against accidental disengagement. In the form shown one member has a projection or reduced end c³, which is received by a mating recess c⁴ in the companion member and snugly held therein.

70 With leaf-fasteners of this description the leaves may be conveniently shifted to the right or left of the book and the leaves may be inserted and removed readily, whereby the different leaves, if forming a ledger, for instance, may be in use by a number of bookkeepers. The ready removal and replacing 75 of the leaves is due to the fastener members being pivoted to swing in their own plane instead of having a lateral movement, as usual. 80

Having thus described my invention, I claim as new and desire to secure by Letters Patent—

1. A file and binder, comprising covers connected by a back, and fasteners for the leaves 85 arranged on one of the covers adjacent to the back, said fasteners consisting of bent or curved members pivoted together in a recess in the cover and having an interlocking engagement at their free ends.

2. The file and binder comprising suitable covers, a plate fastened to one cover, and fasteners for the leaves, composed of members of approximately U shape pivoted together beneath the plate and held to the latter, the free ends of the fastener members being formed to engage each other.

3. The file and binder comprising suitable

covers, a plate fastened to one cover, and fasteners for the leaves, composed of members of approximately U shape pivoted together beneath the plate and held to the latter, the free 5 ends of the fastener members being formed to engage each other, the plate being recessed at opposite sides and bent upward between the

recesses to accommodate the fastener members, and the free ends of the fastener members being formed to engage each other.

ADOLPH A. HUNZIKER.
